INERTIA RESPONSIVE TURNING AND STOP
SIGNAL FOR MOTOR VEHICLES OR SIMI-
LAR ARTICLE

Eli Allen Weston, 3512 Shasta Ave.,
Boise, Idaho 83703

Filed Apr. 26, 1968, Ser. No. 11,633

Term of patent 14 years

Int. Cl. D29—99

U.S. Cl. D72—1

FIG. 1

FIG. 2

FIG. 3

FIG. 4

FIGURE 1 is a front isometric view of the inertia responsive turning and signal for vehicles or similar article embodying my new design in rest position.

FIGURE 2 is a rear isometric view thereof.

FIGURE 3 is a front elevational view of the signal responding to a left turn.

FIGURE 4 is a front elevational view of the signal responding to, slowing or stopping of the vehicle or the like.

I claim:

The ornamental design for an inertia responsive turning and stop signal for motor vehicles or similar article, substantially as shown.
